UNITED STATES PATENT OFFICE.

HARRY C. ADAM, OF ST. LOUIS, MISSOURI, ASSIGNOR TO THE REFLECTOLYTE COMPANY,
OF ST. LOUIS, MISSOURI, A CORPORATION OF MISSOURI.

CONCEALED-TERMINAL RECEPTACLE.

1,297,772.

Specification of Letters Patent. Patented Mar. 18, 1919.

Application filed July 27, 1917. Serial No. 183,124.

To all whom it may concern:

Be it known that I, HARRY C. ADAM, a citizen of the United States, residing at St. Louis, Missouri, have invented a certain new and useful Improvement in Concealed-Terminal Receptacles, of which the following is a full, clear, and exact description, such as will enable others skilled in the art to which it appertains to make and use the same.

This invention relates to electrical receptacles of the type that comprise a one-piece insulator provided with concealed terminals.

15 The main object of my present invention is to provide an efficient electrical receptacle of the type referred to which is so constructed that the workman who installs same has easy access to the binding screws of the 20 terminals and can see said screws clearly during the operation of connecting the supply wires to the terminals, thereby tending to reduce the liability of producing a short circuit during the operation of installing the 25 electrical receptacle.

Figure 1 of the drawings is a side elevational view of a concealed electrical receptacle constructed in accordance with my invention.

30 Fig. 2 is a vertical sectional view of same, taken on the line 2—2 of Fig. 1.

Fig. 3 is a bottom plan view of the receptacle; and

35 Fig. 4 is a detail horizontal sectional view taken on the line 4—4 of Fig. 1.

Referring to the drawings, which illustrate the preferred form of my invention, A designates the insulator of the receptacle which consists of a one-piece member formed 40 of porcelain or other suitable insulating material and provided with a top portion 1 and a cylindrical portion 1^a that are integrally connected together. A screw-threaded shell 2 of conventional form is arranged inside 45 of the cylindrical portion 1^a of the insulator and is connected to the top portion 1 of the same by means of screws, and the two terminals of the receptacle are arranged in openings in the cylindrical portion 1^a of the 50 insulator in such a manner that they are protected by the top portion 1 of the insulator, thus producing an electrical receptacle that complies with all of the requirements of fire prevention officials as to the location of 55 the terminals, but which has the distinguish-

ing and desirable characteristic of accessible binding screws that can be clearly seen by the workmen during the operation of connecting the supply wires to the terminals of the receptacle. In the form of my invention herein shown the contact 3 of the receptacle is provided with a terminal 4 that is equipped with a binding screw 4^a, and the contact 5 is provided with a terminal 6 that is equipped with a binding screw 6^a. Said 60 terminals 4 and 6 are arranged diametrically opposite each other in openings 7 formed in the side wall of the cylindrical portion 1^a of the insulator in proximity to the top portion 1 of the insulator. If desired, each of said openings 7 can be provided with a lateral offset 7^a, preferably formed by a groove in the outer surface of the cylindrical portion 1^a of the insulator, so as to receive the supply wire x, as shown 75 in Fig. 4, and thus permit the supply wires to be arranged substantially tangential to the cylindrical portion 1^a of the insulator. The top portion 1 of the insulator is enough 80 larger than the cylindrical portion 1^a to produce a flange at the upper end of the insulator that forms an adequate protection for the terminals. The terminals 4 and 6 are also preferably arranged some distance inwardly from the outer surface of the cylindrical portion 1^a of the insulator so that the 85 binding screws and the ends of the supply wires that are connected to the terminals will be located within the marginal limits of the cylindrical portion 1^a of the 90 insulator. The top portion 1 of the insulator is provided with two laterally-projecting ears arranged diametrically opposite each other, as shown in Fig. 3, and each is provided with a hole 8^a through which 95 screws can be inserted so as to secure the insulator to a ceiling or other supporting structure arranged above the insulator.

An electrical receptacle of the construction above described complies with all of the requirements which fire prevention officials have decided are essential for so-called concealed terminal receptacles, and it also has a feature that none of the one-piece concealed terminal receptacles now in general 100 use possess. Namely, the terminals of same and the binding screws on said terminals are clearly exposed to view, thus permitting the workman who installs the terminal to clearly 105 see what he is doing when connecting the 110

supply wires to the terminals, and consequently, eliminating the possibility of producing short circuit, as so often occurs in connecting up concealed terminal receptacles of the kind now in general use.

Having thus described my invention, what I claim, and desire to secure by Letters Patent, is:

An electrical receptacle, comprising a one-piece insulator provided with a cylindrical portion and a top portion integrally connected together, said top portion projecting laterally beyond said cylindrical portion so as to form a protecting flange, laterally pro-

jecting ears on said top portion through which screws or connecting devices can be passed, the cylindrical portion of the insulator being provided in its sides just below said flange with openings that extend clear through same, contacts carried by said insulator and provided with terminals arranged in said openings in such a manner that the binding screws on the terminals will lie within the marginal limits of the cylindrical portion of the insulator, and wire receiving grooves extending tangentially from said openings.

HARRY C. ADAM.
